United States Patent Office

Des. 191,771
Patented Nov. 14, 1961

191,771

WALL MOUNTED WATER COOLER OR SIMILAR ARTICLE

Louis P. Benua, Columbus, Richard J. Radcliffe, Worthington, and William Taylor, Columbus, Ohio, assignors to The Ebcu Manufacturing Company, Columbus,
Ohio, a corporation of Ohio

Filed Aug. 17, 1960, Ser. No. 61,794

Term of patent 14 years

(Cl. D67—4)

3

4

FIG. 1 is a perspective view of a wall mounted water cooler or similar article embodying our new design;

FIG. 2 is a front elevational view thereof;

FIG. 3 is a side elevational view thereof; and

FIG. 4 is a top plan view thereof.

We claim:

The ornamental design for a wall mounted water cooler or similar article, substantially as shown.
